UNITED STATES PATENT OFFICE.

MANOUS H. BURTON, OF CEDAR RAPIDS, AND BENJAMIN F. BURTON, OF WATERLOO, IOWA.

COAT AND HAT HANGER.

SPECIFICATION forming part of Letters Patent No. 763,461, dated June 28, 1904.

Application filed May 16, 1903. Serial No. 157,490. (No model.)

To all whom it may concern:

Be it known that we, MANOUS H. BURTON, residing at Cedar Rapids, in the county of Linn, and BENJAMIN F. BURTON, residing at 5 Waterloo, in the county of Blackhawk, State of Iowa, citizens of the United States, have invented certain new and useful Improvements in Coat and Hat Hangers, of which the following is a specification.

10 This invention relates to devices for locking coats and hats in hotels and other public places; and the object of the invention is to produce a simple, cheap, and durable device for the purpose and adapted to hold securely 15 a hat or garment hung upon it.

The nature of the invention will fully appear from the description and claims following, reference being had to the accompanying drawings, in which—

20 Figure 1 is a front view of a locker embodying our invention. Fig. 2 is a side view of the same, partly sectional. Fig. 3 is a fragmentary front view showing a modification in construction. Fig. 4 is a longitudinal section 25 of the lock. Fig. 5 is a cross-section of the same in the line *a b*. Fig. 6 is a sectional view of the key.

In the drawings, A is a base-plate, of comparatively thin and narrow steel, which may 30 be attached directly to the wall, but is preferably secured to a base-block B and is fastened to the wall by screws C C. To the base-plate is secured, as by riveting, one or more hooks D, forming supports for hats, coats, or 35 other garments. To the base-plate is also attached the lock, which will be described hereinafter. Directly over the base-plate is a sliding plate E, provided with hooks F, which may be similar to the hooks D, but inverted. 40 All the hooks are tipped with elastic end pieces G, of rubber or other suitable material. The lower hooks pass through slots E' in the sliding plate, which may thus move up or down a limited distance to allow a hat or coat to be 45 placed between the hooks easily. At some suitable place (the lower end, as herein illustrated) the sliding plate is serrated on its outer face, as shown at E'', such serrated portion

entering the lock-case H through suitable openings therein. Within the lock-case is 50 pivoted a pawl I, normally held in engagement with the serrated plate by a spring J. The pawl is released by the engagement of a key K with an extension or tail of the pawl I'. The sliding plate is preferably returned 55 to elevated position when released by the pawl by a spring L, connecting with the plate at one end and at the other end attached to the base-block by a suitable pin M or the like. Provision is made for the action of this spring 60 by slotting the base-plate at A'. This spring might be dispensed with and the sliding plate raised by the hand of the operator; but the automatic action is preferred.

Hats or garments placed in the position indicated are locked between the tips of the upper and lower hooks by simply drawing down the slide-plate and its connected hooks, one of the hooks being used for the purpose. 65

Ordinarily there is so little difference between the thickness of a hat-crown and the material of a coat that the elasticity of the tips is sufficient to allow for both being held at the same time and by the same action. Provision is made, however, for wide differences in this respect or for independent use 70 of the hooks altogether. In this case the depending hooks are each mounted on a separate slide-bar E', one of which may lie on either side of the upturned hooks, as shown 75 in Fig. 3. Both slide-bars are serrated and enter the lock-case, as shown in Fig. 5. A single wide-nosed pawl would serve to lock both at once; but two pawls are preferred. Between their ends the slide-bars are guided 80 and held in place by one or more stirrups N. In its simplest form the lock is composed of the case, (two pieces of thin steel bent in stirrup form and fitting together, as shown,) a pawl with a spring to press it into engagement with the notches of the slide-bar, and a key having a lateral extension to engage the tail of the pawl. For greater security against picking, however, the lock is provided with a ward-plate O, with one or more projections 85 O' thereon, and the wing of the key opposite 90

the pawl is notched at K' to allow the projection to pass as the key is turned. A great many changes may be made in the locks and keys by shifting the positions of the pawl-lifting fingers K² and of the notches in the opposite wing, the positions of the pawls and of the ward projections being made to register therewith, of course. The pawls may be easily shifted by the interposition of washers 5

10 Q and the projections on the ward-plate as easily changed in the initial operation of punching. As a further safeguard against the lock-pick a stop-plate R may be pivoted in the lock-case so as to hang normally in a

15 position to lock the pawl. When the key is inserted and turned, however, a finger K³ engages the inclined face of a depending finger R' and lifts the stop-plate into register with a notch I² in the pawl. When depressed, the

20 finger R' rests on a stop-stud S. The turn of the key is also limited by a stud T, which engages a shoulder K K⁴.

Wherever possible the parts of the locker are formed of wrought-steel punched and 25 stamped in the proper forms. By reason of this the device is made unbreakable and a neat, light, and inexpensive device is secured.

Instead of solid and comparatively thick metal for the hooks, as indicated in Fig. 3, 30 the hooks may be died out of thin material with a web at each side, as shown in Fig. 2. In this case a band may be formed at the outer end to embrace the neck of the rubber tip as pressed thereon.

35 One of the special advantages arising from this construction is that the locker admits and holds articles differing greatly in thickness, the range of notches in the slide-plate being

great enough to lock anything from a hand-kerchief to a parcel of considerable size.

Having thus described our invention, what we claim as new, and desire to secure by Letters Patent, is—

1. A locker for hats or coats, comprising a flat base-plate with a hook attached thereto, a similar slide-plate with an oppositely-disposed hook attached thereto, a slot in the slide-plate through which the hook of the base-plate extends, a stirrup to hold the two plates in sliding contact, face to face, a series of notches in the face of the slide-plate, and a lock to engage therewith, the lock-case being attached to the base-plate with an opening to receive the serrated portion of the slide-plate, substantially as described. 50

2. In a locker, the combination of a narrow, straight, flat base-plate, provided with a hat-hook, a stirrup, and a lock, a similar slide-plate with an oppositely-projecting hook thereon, slotted to allow the base-plate hook to pass through it and the slide-plate to move up and down, a series of notches in the face of the slide-plate, a pawl in the lock to engage the same, a slot in the base-plate, and a spring mounted therein, one end connecting with the slide-plate and the other with the base-plate. 60

In testimony whereof we affix our signatures in presence of two witnesses.
